UNITED STATES PATENT OFFICE.

FRANK HERKENRATH, OF SANTIAGO, CHILE.

AUTOMATIC FEEDER.

Application filed July 28, 1925. Serial No. 46,542.

This invention relates to mechanism for automatically feeding fuel into the fireboxes of furnaces, the object of the invention being to provide an improved apparatus of this character in which the automatic feeding of the fuel is accomplished by a series of alternating slow backward and rapid forward movements of the grate, and the sudden stopping of the forward movement, and in 10 which device provision is made for regulating the extent of such movement.

A further object of the invention is to provide an apparatus of this character having means for regulating the amount of fuel 15 supplied to the firebox at each forward movement of the grate.

With the foregoing and other objects in view, which will appear as the description proceeds, the invention consists in the novel 20 features of construction and combination of parts which will be more fully described hereinafter and particularly pointed out in the claims.

In the drawings accompanying and forming part of this specification,

Fig. 1 is a vertical longitudinal section of an apparatus embodying the features of the present invention, the section being taken approximately on the line I—I of Fig. 2.

30 Fig. 2 is a front elevation thereof.

Fig. 3 is a fragmentary rear view of the chute illustrating the gear and rack mechanism for raising and lowering the fuel door.

The same characters of reference designate the same parts in the different figures of the drawings.

Referring to the drawings, the feeder consists of a supporting frame adapted to be disposed in front of the firedoor of a furnace, 40 as is customary. The frame comprises a pair of uprights or standards 2 and 3, one at each side, said standards being bolted to suitable bases 4 provided therefor in the floor of the building. Mounted on these standards is a fuel chute 5, preferably rectangular in cross section and funnel-shaped in side elevation, the chute being secured to the standards by means of angle irons 14 and bolts 15. The chute is provided at the 45 side thereof adjacent to the firebox with a regulator or door 6, said door being vertically movable between guides 7 secured on the inner surfaces of the side walls of the chute. For the purpose of raising and lowering said door and thereby controlling the amount of fuel passing through the opening

8, a shaft 13 is mounted in bearings carried by the side walls of the chute, said shaft carrying a pair of pinions 11 in mesh with a pair of vertical racks 10 carried by the 60 door 6. The shaft 13 also has fixedly mounted thereon, exteriorly of the chute, a pinion 12 in mesh with a toothed segment A carried at one end of a lever 9 pivoted in one of the side walls of the chute. It will thus 65 be seen that by swinging the lever on its pivot the door 6 may be raised or lowered, thereby increasing or decreasing the size of the opening 8 and permitting more or less fuel to pass into the furnace.

The furnace is provided with a vibratory grate, designated generally by 16, which is supported independently of the frame above described, and which comprises a pair of longitudinal iron bars 17 secured at one end to a transverse end member 18, the bars being connected together near their opposite ends by a plate 19, thus forming a very rigid and substantial frame. Mounted on the side bars 17 and plate 19 in position to close the lower 70 end of the chute 5, is a table 40 carrying brackets 20 adapted to support one end of a series of inclined grate bars 22, the opposite ends of said grate bars being seated in a recess 21 formed in the end member 18. A 75 pair of side walls 23 are provided, one at each side of the grate carrying frame, thereby to direct the fuel toward the ash pit.

The grate carrying frame above described is mounted for oscillatory movement, and 80 for this purpose the side bars 17 are provided with a plurality of depending pivot brackets 28, a plurality of similar brackets 29 being mounted on the base and each disposed in vertical alinement with one of the brackets 95 28 when the grate is at the limit of its inward movement, as shown in Fig. 1, the brackets 28 and 29 being connected together by pivoted links 30. The grate-carrying frame is thus capable of horizontal oscillatory movement whereby the table 40 is caused to swing beneath the chute 5. A shaft 31 is mounted in boxes B carried at the forward ends of the side bars 17, said shaft having mounted thereon a pair of rollers 34 disposed at equal 100 distances from the boxes B. For oscillating the grate frame, a second shaft 25 is mounted in bearings carried by a fixed part of the frame of the apparatus, said shaft having secured thereon a pair of cams 26 disposed 105 in alinement with the rollers 34, while a pulley 27 is secured on one end of shaft 25 110

for transmitting rotary motion to said shaft from any suitable source of power (not shown). A pair of springs 35 are secured each at one end thereof to a cross bar 38 secured to the standards 2 and 3, and at the opposite end, by means of nuts 37 to depending brackets 36 carried by the plate 19.

For regulating the extent of movement of the grate-carrying frame, the shaft 31 has secured thereon a pair of eccentrics 32, one adjacent to each end thereof, each of said eccentrics being mounted for rotation in one of the bearing boxes B'. A hand lever 33 is secured to the shaft at one end thereof, whereby the shaft and its eccentrics may be rotated in the bearing boxes B thereby to impart to the shaft a planetary motion so as to carry the rollers 34 further away from or nearer to the cams 26, whereby the latter will impart to the grate a shorter or longer reciprocatory movement.

The operation of the machine is as follows:

Fuel is supplied to the chute 5 from any convenient source and in any suitable manner. The pulley 27, upon being connected to a slowly rotating driving shaft, rotates the shaft 25 and thus carries the cams 26 into contact with the rollers 34, thereby pushing the shaft 31 away from the shaft 25, and since the shaft 31 is mounted in boxes B which are carried by the side bars 17 of the grate frame, the latter is caused to move forward beneath the chute 5 and the springs 35 are placed under tension. As soon as the limit of the eccentric action is reached, which is when that portion of the cams having the greatest radius is in contact with the rollers, by the continued rotation of the shaft 25 the portion of the cams having the shortest radius is presented to the rollers 34, whereupon, by the action of the springs 35 the grate frame is given a sudden and rapid movement in the opposite direction, thus carrying a new charge of fuel into the furnace. The end member 18 of the grate frame is

provided with bumpers 39 disposed in position to contact with similar bumpers secured in the wall of the furnace, said bumpers thus sharply stopping the movement of the oscillatory grate frame. By reason of the rapid advance of the grate frame and the sudden stopping thereof by the bumpers 39, the fuel is caused by the force of inertia to advance a step toward an open space communicating with the ash pit, the width of which space is regulated by the setting of the eccentrics on the shaft 31 in the boxes B. Openings 41 may be formed in the side walls of the standards 2 and 3 for the admission of air to the combustion chamber.

Having thus described my invention, what I claim is:

1. An automatic fuel feeding device, comprising a horizontally reciprocatory grate frame, an inclined grate supported in said frame, side walls carried by said frame and movable therewith, means for supplying fuel to said grate, means for moving the grate frame in one direction at a comparatively slow speed, means for varying the extent of said movement, means for imparting to the grate frame a rapid movement in the opposite direction, and means for suddenly stopping said last movement.

2. An automatic fuel feeding device, comprising a horizontally reciprocatory grate frame, an inclined grate supported in said frame, side walls carried by said frame and movable therewith, means for supplying fuel to said grate, means for regulating the fuel supply, means for moving the grate frame in one direction at a comparatively slow speed, means for varying the extent of said movement, means for imparting to the grate frame a rapid movement in the opposite direction, and means for suddenly stopping said last movement.

In testimony whereof I hereunto affix my signature.

FRANK HERKENRATH.
